UNITED STATES PATENT OFFICE

CLAUDE L. ORR, OF COLUMBUS, OHIO, ASSIGNOR TO THE BUCKEYE STEEL CASTINGS COMPANY, OF COLUMBUS, OHIO

SIX-WHEEL-TRUCK CONSTRUCTION

Application filed August 24, 1928. Serial No. 301,864.

This invention relates to car trucks and has special reference to six-wheel trucks of the type disclosed in Letters Patent No. 1,356,653, issued to me October 26, 1920, the object 5 being to provide a bolster arrangement for six-wheel trucks which will accommodate cars having a wide and low sill construction. The invention provides a one-piece center or longitudinal bolster which rests on the trans- 10 verse bolsters in such manner as to be effectually restrained against lateral movement and provide a support for both the center plate and the side bearing loads.

In the accompanying drawings:

15 Figure 1 is a plan view of a truck embodying the present invention;

Figure 2 is a side elevation of the same;

Figure 3 is a transverse section on the line 3—3 of Fig. 1;

20 Figure 4 is a transverse section on the line 4—4 of Fig. 1.

There are two side frames 1 at each side of the truck with their inner ends disposed side by side and connected by an equalizer 25 frame 2 carrying the bearing for the center axle. Each side frame carries a bearing for an end axle and is also provided with an opening to receive an end of a transverse bolster 3, the transverse bolster being sup- 30 ported seated in the opening and being located between the center axle and an end axle. Each transverse bolster 3 is provided with vertical shoulders 4 near its ends and is of a dished formation, its ends being somewhat 35 higher than its central part and being connected therewith by upwardly and outwardly inclined portions 5.

The center or longitudinal bolster 6 is a single integral casting of a general channel 40 form in transverse section, the central web 7 being below and connecting the side members or turned up flanges 8, as will be understood on reference to Figs. 3 and 4, and the bolster is rectangular in outline when viewed in plan. 45 The web 7 includes end members 9, connecting the side members 8 at the ends thereof, a central member 10, also connecting the side members, and longitudinal members 11 connecting the central and end members, the 50 members 10 and 11 forming a cross which

provides a support for the center plate. The ends of the center bolster rest upon the transverse bolsters 3 and the side members or turned up flanges 8 terminate in downturned hooks 12 which bear against the outer sides 55 of the transverse bolsters and thereby prevent shifting of the center bolster longitudinally of the truck. These down-turned terminal hooks also bear against the shoulders 4 and thereby aid in preventing relative 60 transverse movement of the center bolster. The corners of the center bolster are tapered upwardly and outwardly (Fig. 4) on lines 13 corresponding to the inclined end portions 5 of the transverse bolsters and pads 14 are 65 formed on tapered corners to bear upon the transverse bolsters, a wide support for the central bolster being thus provided as well as an aid to the shoulders 4 in preventing transverse movement of the same. The side 70 members or flanges 8 are, of course, parallel with the side frames 1 and they rise at their centers above the side frames, as shown in Fig. 2, and are formed with brackets 15 adjacent the center wheels and symmetrical 75 about the central transverse line of the bolster to supporting tables for the side bearings. The center bearing plate 16 may be formed integral with the bolster or a separate plate may be bolted or riveted in place. 80

The channel form of the center bolster provides ample strength and provides space between the side members 8 which allows the use of wide center sills on the car body. The center bolster transmits both the side bearing loads and the center plate load to the side frames through the transverse bolsters, and there is sufficient space available for the accommodation of efficient brake rigging. 85

Having fully described my invention what 90 I claim as new and desire to secure by Letters Patent, is:—

1. In a six-wheel truck a combination of two transverse bolsters, a one piece rectangular shaped center bolster having its only support at its four corners which bear on the transverse bolsters. 95

2. In a six-wheel truck a combination of two transverse bolsters, springs on which the bolsters are seated, a center bolster mounted 100

on and bearing at its four corners only on the transverse bolsters and securely held in place by locking lugs; the center bolster having an integral center plate or a table at the center on which a separable center plate may be riveted.

3. In a six-wheel truck, the combination of a plurality of transverse bolsters having inclined bearings, and a center bolster seating on the transverse bolsters only at said bearings, and having brackets projecting upwardly and outwardly from the side members thereof and forming side bearings.

4. In a six-wheel truck, a combination of two transverse bolsters supporting a center bolster; the center bolster having a channel section with the flanges turned up at its side edges, said center bolster being provided with a plate at its middle and bearing on the transverse bolsters only at its four corners.

5. In a six-wheel truck, a combination of two transverse bolsters supporting a center bolster having a channel shaped section transversely through its ends, the bearing surfaces at its four corners tapering upward and outward from their inside edge.

6. In a six-wheel truck the combination of truck side frames, two transverse bolsters carried by the latter, a rectangular shaped center bolster mounted only at its four corners on the transverse bolsters, having a center plate at its middle and side bearing tables on its outer sides.

7. In a six-wheel truck, the combination of two transverse bolsters having upwardly and outwardly inclined portions near their ends, and a center bolster having its corners tapered upwardly and resting on said inclined portions of the transverse bolsters.

8. In a six-wheel truck, the combination of two transverse bolsters having vertical shoulders on their outer sides and having upwardly and outwardly inclined portions near their ends, and a center bolster having its corners tapered upwardly and resting on said inclined portions of the transverse bolster and having downturned hooks at its ends bearing against the outer sides of the transverse bolsters and against the vertical shoulders thereon.

9. In a six-wheel truck, the combination of transverse bolsters having their central portions depressed relative to their end portions, springs on which said bolsters are seated and a center bolster resting only at its corners on the transverse bolsters and having relatively elevated side members.

10. In a six-wheel truck, a combination of two transverse bolsters, and a one-piece rectangular shaped center bolster having four inclined bearings seating on the transverse bolsters.

11. In a six-wheel truck, a combination of two transverse bolsters, and a center bolster resting thereon and consisting of crossed

median members formed integrally with a rectangular frame-work.

12. In a six-wheel truck, side frames, each comprising end members and a central equalizing member, the end members of each side frame overlapping and being pivotally connected to the ends of the equalizing member, each of said end members having a bolster opening therein, transverse bolsters having their ends arranged in said openings, and a longitudinal bolster provided with a center plate and having its ends superposed upon the tops of the transverse bolsters.

In testimony whereof, I have signed this specification.

CLAUDE L. ORR.
